PRODUCTION OF HIGH CONCENTRATED
FIXING AND HARDENING SIRUPS

Garnet Philip Ham, Old Greenwich, Conn., assignor to American Cyanamid Company, New York, N. Y., a corporation of Maine

No Drawing. Application November 30, 1940,
Serial No. 367,955

6 Claims. (CL 95—88)

This invention relates to the production of stock fixers and hardeners for silver halide photographic material.

In the past photographic fixing and hardening baths containing an alum as well as the soluble sodium thiosulfate and sulfite, were either prepared by dissolving the chemicals to form a bath of normal concentration, usually about 250 grams of sodium thiosulfate to the liter, or the bath is made up in liquid form in which form it keeps for a reasonably long time. There has been a considerable demand for high strength sirups that could be diluted with water especially by users such as physicians and dentists who are not trained photographers and who wish to be able to fix their X-ray films with a minimum of time. Such high concentration sirups are of course of great advantage because it is possible to rapidly dilute them with water to the desired strength without dissolving any chemicals or without having to store relatively large volumes of normal strength fixing baths.

If it is attempted to prepare high concentration sirups using either sodium thiosulfate or preferably mixtures containing guanidine thiosulfate which show higher solubility, these sirups cannot be readily made by dissolving up the various ingredients in the normal manner. On the contrary, when it is attempted to make such sirups containing for example 1000-1200 grams of thiosulfate to the liter, precipitation takes place.

According to the present invention I have found that if the thiosulfate and part of the sulfite are dissolved separately and the alum, acid, and remainder of the sulfite dissolved in a separate solution, and then mixed, preferably cold, no precipitation results and stable high concentration fixing sirups are obtained.

It is not desired to limit the present invention to any theory of action but it is my opinion that probably a factor of importance lies in the avoidance of excessive local concentrations where some of the solid materials are dissolving. The two solutions mix rapidly and completely and excessive concentrations in isolated zones are not obtained. It is of course possible that other factors may be present and may even be of greater importance.

Excellent sirups can be prepared as described above, but when guanidine thiosulfate mixtures are prepared by using the portions of guanidine nitrate with sodium thiosulfate, the sirups are sometimes not completely clear although usable. If, however, they are filtered through unactivated wood charcoal, they are completely clear and

show excellent stability. I do not wish to limit this feature of the invention to any particular theory but I am of the opinion that an important factor lies in small amounts of impurities which are usually associated with technical guanidine nitrate and which are probably adsorbed or removed by the charcoal filtration. When perfectly chemically pure guanidine nitrate is employed, the filtration is not normally required. This feature, while not an essential to the invention, is of large practical importance as it permits the use of technical guanidine nitrate with a corresponding very marked saving in cost and therefore forms part of the preferred embodiment of the present invention.

By means of the present invention it is possible to obtain fixing sirups containing guanidine thiosulfate up to about 1000-1200 grams of thiosulfate per liter. Higher concentrations may be produced by the incorporation of hydroscopic materials such as urea. In the present case I do not claim the addition of hydroscopic generally as this forms the subject matter of the copending patent of Ham and Barnes No. 2,248,905, issued July 8, 1941.

The invention will be described in conjunction with the following specific examples.

EXAMPLE 1

30 Two solutions were prepared as follows:

Solution A

	Parts
Water	700
Sodium sulfite (anhydrous)	30
Sodium thiosulfate (5H ₂ O)	1000
Guanidine nitrate	208

Solution B

	Parts
Water	300
Acetic acid (28%)	200
Boric acid	30
Potassium aluminum sulfate	60
Sodium sulfite	32

During solution the temperature should preferably be kept under 50° C. and finally the two solutions should be cooled to room temperature. Solution A is then filtered through unactivated wood charcoal to remove traces of insoluble material from the guanidine nitrate used, and solution B is then mixed with solution A. A sirup was obtained of medium viscosity, light yellow in color, and when diluted with 3 parts of water, it produced a clear solution which at 24° C. fixed ortho-

portrait film in approximately 2 minutes and X-ray film in about 1½ minutes. The sirup shows excellent stability and at room temperature does not show any precipitation after 30 days. At higher temperatures, however, about 49° C., considerable sulfurization results after about six days.

When the same materials are used but the solids dissolved in the order—sodium sulfite, guanidine nitrate, sodium thiosulfate, acetic acid, boric acid, potassium aluminum sulfate—a heavy precipitation was formed containing precipitate showing sulfur and an aluminum complex. Even after filtering a precipitate reappears.

Higher stability especially at high temperatures may be obtained by incorporating 36 parts of urea in solution A before filtering through charcoal. This sirup is not only completely stable at room temperature but also at 6° C. and 49° C. respectively. Difficulty is encountered even with the powerful hydroscopic substance, urea, if the ingredients are dissolved one after the other without preparing the two separate solutions. Other hydroscopics such as those described in the Ham and Barnes patent above referred to, may be substituted for the urea.

EXAMPLE 2

A concentrated fixer and hardener sirup was prepared by forming the following two solutions:

Solution A

	Parts
Water	350
Sodium thiosulfate (5H ₂ O)	600
Sodium sulfite (anhydrous)	15

Solution B

	Parts
Water	150
Acetic acid (28%)	100
Boric acid	15
Potassium aluminum sulfate	30
Sodium sulfite (anhydrous)	16

The solutions were mixed together, filtered

through unactivated charcoal as described in the preceding example, and gave a satisfactory fixing and hardening solution when diluted with water.

In the above examples potassium alum is used and in a similar manner chrome alum may be employed although the stability of the resulting solution is not quite as high.

What I claim is:

1. A method of preparing a high concentration stable fixing and hardening solution for silver halide photographic material containing a soluble thiosulfate in amounts of the order of magnitude of 1000 to 1200 grams per liter, sulfite, and alum hardener which comprises dissolving in water the desired amount of soluble thiosulfate and at least a considerable portion of the sulfite, separately dissolving in water the alum hardening ingredients under acid conditions, and mixing the two solutions together.
- 10 2. A method of preparing a high concentration stable fixing and hardening solution for silver halide photographic material containing a soluble thiosulfate in amounts of the order of magnitude of 1000 to 1200 grams per liter including guanidine thiosulfate in effective amounts, sulfite, and alum hardener which comprises dissolving in water the desired amount of soluble thiosulfate and at least a considerable portion of the sulfite, separately dissolving in water the alum hardening ingredients under acid conditions, and mixing the two solutions together.
- 20 3. A method according to claim 1 in which a hydroscopic substance is incorporated in the first solution.
- 30 35 4. A method according to claim 2 in which a hydroscopic substance is incorporated in the first solution.
- 35 5. A method according to claim 1 in which urea is incorporated in amounts sufficient to exert a hydroscopic action on the thiosulfate.
- 40 6. A method according to claim 2 in which urea is incorporated in amounts sufficient to exert a hydroscopic action on the thiosulfate.

GARNET PHILIP HAM.
